2 SHEETS—SHEET 2.

UNITED STATES PATENT OFFICE.

CHARLES C. HUBER, OF ROCHESTER, NEW YORK.

GARBAGE CONTAINER.

1,427,472.

Specification of Letters Patent. Patented Aug. 29, 1922.

Application filed May 21, 1921. Serial No. 471,300.

To all whom it may concern:

Be it known that I, CHARLES C. HUBER, a citizen of the United States of America, and residing at Rochester, in the county 5 of Monroe and State of New York, have invented certain new and useful Improvements in Garbage Containers, of which the following is a specification.

My invention relates to a garbage container and the principal object is to afford 10 a durable, practical and efficient structure of the underground type.

In a more particular aspect, the invention has for its object to provide a concrete, cement, or artificial stone body portion 15 adapted to be sunk in the ground, and having associated therewith a cover and covering operating means which are protected against rain and moisture, and which are 20 in every way efficient from a mechanical viewpoint.

A further purpose of the improvement is to afford a structure wherein the cover-operating means is, in large measure, completely embedded and housed within the 25 concrete structure of the body.

Another purpose of the invention is to afford a concrete body construction in which a cover is opened by depressing a 30 part of the operating means, and is automatically closed again when such depressible part is released.

Still an additional object of the invention is to afford an arrangement of operating 35 means including a flexible shaft, such operating means having endwise movement within a suitable guideway or tube, for opening the cover.

Another purpose of the invention is to 40 utilize a cover of metal or similar material, in conjunction with a body of concrete or the like, and accomplish this by arranging the cover on supports which are partially embedded in the body.

Other objects and advantages of the 45 invention will appear clearly from the following description, taken in conjunction with the accompanying drawings, the novel features being pointed out in the claims at the end of the specification.

In the drawings:—

Figure 1 is a side elevation of a garbage container, illustrating a preferred embodiment of the invention.

Figure 2 is a plan view of the same.

Figure 3 is an enlarged side elevation, showing the manner in which the cover is hinged to the body.

Figure 4 is a vertical sectional view on line 4—4 of Figure 2, and showing, in dotted 60 lines, the open position of the cover.

Figure 5 is an enlarged sectional view illustrating the relation of the operating means and the actuating member of the cover.

Figure 6 is a sectional view of the operating means, before it is embedded in the body.

Figure 7 is a sectional view on line 7—7 of Figure 6.

Figure 8 is a sectional view on line 8—8 of Figure 2.

Figure 9 is an enlarged sectional view on line 9—9 of Figure 3, and

Figure 10 is a perspective view of the 75 cover supporting plate.

In the embodiment illustrated, which is intended merely as an example of one possible adaptation and not as limiting the invention to any particular form, A designates the body which is preferably formed of concrete, artificial stone, or similar material that is cast or poured into form, and adapted to be placed in an opening in the ground and to receive a removable receptacle 85 B. Where I employ the term "concrete" in the following claims, I intend to cover the use of cement, artificial stone, or any other similar non-metallic substance.

Near its upper end, the body A is provided with an annular reinforcement *a* embedded therein, and serving to strengthen the structure, and to prevent spreading or cracking at the upper end. Arranged upon the body, in a manner that will be described 90 presently, is a cover consisting of inner and outer metallic walls C, C', which are spaced from each other as shown in Figure 4, and held together by bolts *c* fixedly secured to the outer wall, and nuts *c'*, which 95 cooperate with the ends of said bolts and engage the inner wall. The outer wall C' is extended beyond the inner wall to afford a collar or flange *c*², which extends downwardly around the outside of the body when 100 the cover is closed. Positioned in the space between the inner and outer walls C, C', is a packing of mineral wool or other similar absorbent material, which serves to insulate the interior of the body, thereby 105 pre- 110

venting access of heat in summer and cold in winter.

Fixedly secured to the cover is a curved plate D, provided with ears d, which latter are mounted on and fixed to the rod E, which in turn is journaled in suitable stationary supports. To this end, the body is provided with projecting portions or abutments f, within which are embedded the lower 10 ends of supports g, the upper ends of said supports having openings which receive the rod E. With this arrangement, it will be seen that the rod E is fixedly connected with, and turns with, the cover as the latter is opened or closed. Fixedly mounted upon the rod E is a curved operating arm E', and a curved controlling arm E², which are also movable with the cover and function in the manner that will now be described.

20 The cover is opened by operating means arranged on the body, such operating means having engagement with the operating arm E', and being movable endwise in its cooperation with the latter. The operating means is 25 positioned and travels in a U-shaped guideway, preferably constituted by a tube in the concrete body, and embraces a flexible shaft affording a connection between reciprocable plunger devices in the ends of such guideway.

To accomplish this, I employ the U-shaped tube F, which is embedded in the concrete body and constitutes the guideway in which the operating means is located and moves. 30 Said operating means includes a flexible shaft F' extending throughout the curved portion of the guideway, and a plunger member, F², see Figure 6, which cooperates with the operating arm E'. Arranged to engage the opposite end of the flexible shaft F', is a depressible plunger F³, provided at its upper end with an enlarged portion or head F⁴, constituting a foot engaging portion. Carried by the plunger F³ is a sleeve F⁵, which engages the 40 outer surface of the tube F, see Figure 6, and thereby prevents water or moisture from getting into said tube.

The plunger member F² preferably includes a wick F⁶, see Figure 7, surrounded by 45 a coil spring F⁷, and arranged on the top thereof is a mass of cotton waste or other lubricant-holding material F⁸, which serves to keep lubricated the roller F⁹, that is carried by the plunger and contacts with the actuating arm E'. Thus as the plunger F³ is depressed, the plunger F² is elevated, which causes the actuating arm E' to be moved to the position shown in dotted lines in Figure 4, and thus open the cover. The cover is 50 held open as long as the plunger F³ is held in depressed position, and when the latter is released, the cover is automatically closed.

To this end, I employ a pair of coil 55 springs H, H', which surround the rod E, and are successively put under tension as the

cover is opened. The fixed end h of the spring H engages one support g, while the free end of said spring is formed into a coil h' which lies in the path of the cover as shown in Figure 9. The fixed end h² of the 60 spring H' engages the other support g, while the free end of said spring is bent to form the arm h³, which also lies in the path of the cover, but rearwardly of the point of initial engagement between the cover and coil h', so that as the cover is thrown open, the spring H, which is the lighter of the two springs, is first put under tension and acts as a buffer for the cover to retard its opening movement, and during the final opening 70 movement of the cover, the spring H', which is the heavier of the two springs, is put under tension and thereby provides the power for throwing the cover to closed position when the operating means is released by removing the foot from the head F⁴ of the plunger F³.

It is desirable to retard or cushion the closing movement of the cover, and for the accomplishment of this purpose, a plunger 90 K is provided which cooperates with the controlling arm E². The plunger K is vertically movable in a tube k, which is embedded in the body A, and is actuated upwardly against the controlling arm E² by 95 means of the spring h'. The plunger K is preferably formed hollow to receive a mass of cotton waste or other lubricant-holding material h², which contacts with the controlling arm E². The spring h', through the 100 plunger K and the controlling arm E², cushions the closing movement of the cover, and in a measure, assists the operating means in the opening movement, thus making the parts operate easily, and with very little 105 friction or noise.

The purposes of the invention may be carried out in other ways than by the precise construction set forth and this application is intended to cover any such modifications or 110 departure from the specific disclosure as come within the fundamental features of the invention or of the following claims.

I claim:

1. A garbage container comprising a concrete body, a cover, a U-shaped tube embedded in said body, and actuating means movable in said tube and operatively associated with the cover for opening it. 115

2. A garbage container comprising a concrete body, a cover, an actuating member fixedly connected to the cover, a U-shaped tube embedded in the body, and operating means movable in said tube and having engagement with said actuating member for 120 opening the cover.

3. A garbage container comprising a body, a cover, and operating means including a tubular guideway, a flexible shaft mounted on the body and movable endwise in said tubu- 125 130

lar guideway, said flexible shaft being operatively associated with the cover for opening it.

4. A garbage container comprising a concrete body, a cover, and operating means including a tubular guideway, a flexible shaft arranged and movable endwise in said tubular guideway, the flexible shaft being operatively associated with the cover for opening it.

5. A garbage container comprising a concrete body, a cover, a U-shaped guideway in said body, a flexible shaft arranged in said guideway, a plunger movable in said guideway and having engagement at its lower end with said flexible shaft and cooperating at its upper end with the cover, and a depressible plunger located in the other end of said guideway and engaging the corresponding end of said flexible shaft.

6. A garbage container comprising a body of concrete, a cover, an actuating member connected with the cover, a U-shaped tube embedded in said body, a plunger located in one end of said tube and having engagement with said actuating member, a depressible plunger located in the opposite end of said tube, and a flexible shaft interposed between said plungers.

30 7. A garbage container comprising a body, a cover, and operating means for the cover including a U-shaped tube carried by the body, a flexible shaft movable endwise in the tube and operatively associated with the cover, a depressible plunger engaging one end of said flexible shaft, and a sleeve carried by said plunger and engaging the outer surface of said tube.

8. A garbage container comprising a body, 40 a cover, a curved actuating member connected with the cover, and operating means including a vertically movable plunger engaging said actuating member and a flexible shaft movable endwise for operating said plunger.

9. A garbage container comprising a concrete body, a cover, a curved actuating member connected with the cover, a tube embedded in said body, and a vertically movable plunger arranged in said tube and engaging said actuating member, said plunger consisting of a tubular member, lubricant-absorbing material carried by said member, and a roller contacting with the actuating member.

55 10. A garbage container comprising a concrete body, a cover, a controlling member connected with the cover, a vertically mov-

able plunger arranged in said body and cooperating with said controlling member, and 60 a spring located beneath said plunger and acting to elevate the latter into engagement with the controlling member and thereby retard closing of the cover.

11. A garbage receptacle comprising a concrete body, a cover, a curved controlling rod fixedly connected to the cover, a tube embedded in said body, a plunger arranged in said tube and engaging said curved controlling rod and a spring located beneath said 70 plunger and acting to elevate the latter into engagement with the controlling rod.

12. A garbage container comprising a concrete body, a cover hinged thereon, a pair of curved arms fixedly connected to the cover, 75 one for actuating it and the other for controlling its movement, a U-shaped tube embedded in the body, operating means movable endwise in said tube and cooperating with said curved actuating arm, a vertical 80 tube embedded in said body, and a spring actuated plunger arranged in said vertical tube and cooperating with said curved controlling arm.

13. A garbage container comprising a concrete body, a cover hinged to the body, a curved actuating arm fixedly connected to the cover, a U-shaped tube embedded in the body, and operating means movable endwise in said tube and engaging said curved 90 actuating arm for elevating the cover.

14. A garbage container comprising a concrete body having a guideway therein, a movable cover, and operating means movable endwise in said guideway and cooperat- 95 ing with the cover to open it.

15. A garbage container comprising a concrete body having a U-shaped guideway therein, a movable cover, and operating means including a flexible shaft movable 100 endwise in said guideway and cooperating with said cover to open it.

16. A garbage container comprising a body, a cover, a U-shaped tube mounted on the body, and actuating means movable in 105 said tube and operatively associated with the cover for opening it.

17. A garbage container comprising a body, a cover, a U-shaped tube mounted on the body, and actuating means including a 110 flexible shaft movable endwise in said tube and operatively associated with the cover.

In witness whereof, I have hereunto signed my name.

CHARLES C. HUBER.
